UNITED STATES PATENT OFFICE

2,072,724

NECKTIE

Jack Weisbaum, Cincinnati, Ohio, assignor to The Weisbaum Bros. Brower Company, Cincinnati, Ohio, a corporation of Ohio

Application February 27, 1935, Serial No. 8,507

3 Claims. (Cl. 2—145)

My invention relates to improvements in neckties, and particularly neckties having clasps for securing the folds of the tie in position covering the opening in the shirt front of the wearer.

5 In my Patents Nos. 1,573,885 and 1,644,863, I have disclosed clasps which are permanently fixed in a certain position on the underneath surface of the outer fold of the tie. While such clasps serve their purpose adequately, there is a 10 tendency for them to hold the tie too closely to the shirt front, so that when the wearer bends his chest and neck, the tie has a tendency to pull, which is either a cause of discomfort to the wearer or tends to release the clasp from position in 15 the opening in the shirt. Another disadvantage is that due to different folding operations with successive adjustments of the tie, the clasp has to be adjusted in the shirt front opening in different positions and frequently the position in 20 which the clasp is located is opposite the button and button hole so that the clasp cannot be securely adjusted in position.

A disadvantage of the clasps which have been heretofore used is the tendency of the silk or other 25 material of the tie, or of the shirt to catch on the sharp edges or corners thereof; and to catch on the ends of the pintle on which the clasp halves and the clasp spring is hinged.

In the Langsdorf Patent #1,447,090, improvements in neckties are disclosed in which there is 30 a body portion with a woven fabric resilient lining connected therewith by loose stitching. It is particularly in the manufacture of this type of tie that my novel mounting for a clasp finds its 35 greatest adaptability.

It is the object of my invention to provide a necktie in which a clasp of desired type may be secured to the loose stitching with which the resilient lining is secured in position in the tie. 40 The purpose of the loose stitching is to prevent distortion of the fabric during the adjustment of the tie, because if the lining and tie are immovably secured together, one fabric will stretch a different amount than the other, which will 45 result in a wrinkled appearance of the tie. The ordinary method of securing a resilient lining within a tie as taught in the Langsdorf patent is to extend the end of the stitching thread beyond the last opening in the fabric of the tie body, 50 and to tie a knot say one inch from the last opening through which the thread passes, so that the tie has an exposed end of thread of substantially one inch in length with the knot on the end of it.

55 A further object of my invention is to provide a

clasp formed of two halves with rounded ends, one of which substantially encloses a portion of the other so that there are no rough edges or corners; and to eliminate the pintle entirely so that there are no projecting ends or corners for the 5 material of the tie or of the shirt to catch and tear on.

I propose to mount a clasp close to the end of the loose stitching either on the actual end of the thread or in a loop of the thread adjacent 10 its end.

Referring to the drawing:—

Figure 1 is a perspective view of the large end of a tie having my clasp mounted in one manner in which I propose to mount the same. 15

Figure 2 is a plan view of my novel type of clasp.

Figure 3 is a longitudinal section of the clasp shown in plan in Figure 2, taken on the line 3—3 thereof. 20

I have shown the end 1, of the large end of a necktie composed of a body portion 2, a layer of woven fabric resilient lining 3, connected to the body portion by means of a loosely stitched thread 4, which has a loop 5 adjacent its end, 25 which passes through an eyelet 14 in a clasp generally indicated at 7. The loose stitching then continues through the last opening in the tie and has an exposed end 8 with a knot 9 in it at the end. 30

The clasp illustrated in Figs. 2 and 3 comprises an upper plate 10 and a lower plate 11 positioned opposite each other so that the jaw portions 17 and 18 will register. The lower plate 11 is rounded and curved at the end 12 opposite 35 the jaw portion so as to almost curve back on itself. The upper plate 10 is shorter than the lower plate 11 and the end opposite the jaw 17 is also curved at 13 but the length is shorter than the curved portion 12 on plate 11. By this 40 construction when the two plates 10 and 11 are placed in position the end 13 of the upper plate 10 will lie partially within the curve 12 of the lower plate 11. There is a spring 16 in the shape of a flattened Z which urges the two jaws 17 and 45 18 together and which also holds the two plates 10 and 11 together. The upper plate 10 has two ears folded back and around the upper portion 19 of the spring 16. While the lower plate 11 has two ears folded back around the lower portion 20 of the spring 16. These ears are so positioned on the two halves that the spring 16 holds these two halves in position and at the same 50 time urges the jaws 17 and 18 together. In making my lower plate 11, as by stamping it out, 55

I preferably form a shield 21 thereon. This shield runs up on the two sides of the rear end 12 of the lower plate 11 and thus the rear end of the lower portion of the clasp substantially encloses 5 a portion of the edge of the upper plate 10 of the clasp. A small hole or eyelet 14 may be placed in the end portion 12 of the lower plate 11 to permit the threading of the clasp onto the loop 5, and the upper plate 10 may be provided with a 10 boss 15 to facilitate manipulation thereof. It is apparent from the above description that my novel clasp is a series of curved surfaces partially enclosing each other with no projecting pintle or sharp and ragged edges or corners. The 15 spring of the clasp acts as the means for holding the clasp portions together like a hinge, and there is no pintle in the clasp at all.

Thus with my novel mounting I have provided a convenient way for mounting the clasp and have further provided means which will practically insure there being an adequate amount of exposed end to the thread, which avoids the likelihood of the loose stitching thread being pulled 20

tight and then causing subsequent strains on the fabric during further adjustments of the tie.

Having thus described my invention, what I claim as new and desire to secure by Letters Patent is:

1. In combination a necktie having a body portion and a resilient lining connected therewith by loose stitching and clasping means carried on a loose part of said stitching. 10
2. In combination a necktie having a body portion and a resilient lining connected therewith, loose stitching connecting said body and lining, said stitching having an exposed end portion with clasping means secured to said exposed end portion. 15
3. In combination a necktie body and lining with loose stitching connecting said body and lining, clasping means mounted on said loose stitching, said clasping means having a portion formed as an eyelet with the loose stitching passing 20 through said eyelet.

JACK WEISBAUM.
